COLLAPSIBLE CABINET

Harry Derman, Laurelton, N. Y.

Application December 20, 1939, Serial No. 310,125

10 Claims. (Cl. 312—144)

This invention relates to collapsible cabinets of the type and kind constructed of corrugated or fibre board walls with wood strip reinforcements; and the object of the invention is to provide a cabinet of the character described employing a door frame unit having as a part thereof, sliding doors with means detachably coupling this unit with other detachably related parts of the cabinet; a further object being to provide a cabinet of the character described wherein the top and bottom wall parts as well as the door frame part include reinforced flanges which collectively form reinforcing strips extending along and adjacent peripheral edges of the cabinet; and with these and other objects in view the invention consists in a cabinet of the class and for the purpose specified, which is simple in construction, efficient in use, and which is constructed as hereinafter described and claimed.

The invention is fully disclosed in the following specification of which the accompanying drawing forms a part, in which the several parts of my invention are designated by suitable reference characters in each of the views, and in which:

Fig. 1 is an exploded view showing the separate parts of the cabinet in related positions ready for assemblage.

Fig. 2 is a section on the line 2—2 of the door frame part of Fig. 1 showing the same attached to part of the side walls of the cabinet.

Fig. 3 is a partial section on the line 3—3 of Fig. 1 on an enlarged scale showing the cabinet parts assembled.

Fig. 4 is a partial section on the line 4—4 of Fig. 1 on an enlarged scale showing the parts assembled.

Fig. 5 is a perspective view of one upper corner portion of the assembled cabinet; and

Fig. 6 is a partial view similar to Fig. 2 showing a modification.

In the construction of cabinets of the type and kind under consideration, it has been customary to provide vertically sliding door or closure members, and where laterally movable door members were employed, they were composed of flexible material adapted to extend into side pockets of the cabinet. In the present construction, I employ a door frame unit which is shipped and packed as a unit and in which are disposed laterally moving sliding doors which control the door opening in said frame. The doors are preferably disposed on the outer surface of the frame and also preferably operate within the marginal limits of the cabinet, so that the doors, when in open position, will not conflict with or strike walls

or members disposed at the sides of the cabinet, especially when arranged in a limited storage space.

In the accompanying drawing I have illustrated one embodiment of my invention. In Fig. 1, 10 represents the back and side wall part of the cabinet, 11 represents the top wall part, 12 the bottom wall part, including an upwardly directed integral front wall portion 13, and 14 represents the door frame part. These parts are all collapsible one upon the other to form an elongated relatively thin package which will facilitate storage and shipment thereof. These parts are extended and assembled in a manner such as diagrammatically illustrated in the exploded view, Fig. 1, in which the general relationship of the parts is illustrated.

The part 10 simply consists of a rectangular sheet folded to form a back wall 15 and side walls

16. These walls extend to inner surfaces of the top and bottom wall parts 11 and 12 and fit within downwardly extending flange portions 11a in the top wall part and upwardly extending wall portions 12a of the bottom wall part. The walls are secured in position by suitable fastening devices such as commonly employed, two of these fastening devices being shown at 17 in Figs. 3 and 4 of the drawing.

The top wall 11 also includes a downwardly extending flange portion 11b at the front of the cabinet, and this flange has foldable side tongue portions 11c which form finished corners at the top of the cabinet and are disposed in coplanar alignment with the flanges 11a as well as side flanges 14a on the door frame part 14. The flanges 11a which are disposed at the sides and back of the top wall part 11 are also reinforced by wood strips 18. The forward edges of these strips terminate short of the front of the top wall 11 to abut similar reinforcing strips 18a arranged on the flanges 14a, as is clearly illustrated in Fig. 5 of the drawing.

The foldable front wall part 13 of the bottom wall 12 also includes side flanges 13a which are disposed in alignment with the flanges 12a and 14a. These flanges have wood reinforcing strips 18b which are arranged in alignment with the strips 18a, and reinforcing strips 18c on the sides of the bottom wall part 12 abut the strips 18b which are clearly indicated in Fig. 1. It will be understood that a strip 18c also extends across the rear flange 12a of the bottom wall part. Another reinforcing strip 19 is also preferably disposed at the lower edge portion of the front wall part 13 to guard and protect this edge and to

form a desirable finish to the bottom of the cabinet. The extensions 13b of the flanges 13a are similar to the tongue-like extensions 11c and also abut the flanges 14a on the door frame part as will be apparent.

The door frame part 14 is formed from two strips or panels 20 of fibre or corrugated board, disposed at each side of the door frame and spaced apart to form a large rectangular opening 21 in the door frame. The flanges 14a of the panels are foldable with respect to the panels 20. Coupling the upper and lower end portions of the panels 20 are reinforcing and guide rail strips 22 which are of similar construction. Each strip is provided at one side edge with a single groove 23 and at the opposite side edge with two grooves 24, 25, the groove 24 being the inner groove and the groove 25 the outer groove. The groove 23 in the upper strip 22 receives the flange 11b of the top wall, note Fig. 3, whereas the groove 23 of the bottom strip 22 receives the upper edge portion of the front wall 13, note Fig. 4. The upper and lower edges of the panels 20 are permanently secured in the grooves 24 in forming the door frame 14. This frame is reinforced at inner opposed edges of the panels 20 by vertical reinforcing stop or door check strips 26 which extend onto the inner surfaces of the strips 22 and are secured thereto. It will thus be seen that the strips 26 together with the strips 22 form the border frame for the door opening 21.

Slidably mounted in the grooves 25 of the strips 22 are door members 27, 27a which consist of straight strips of corrugated or fibre board, upper and lower edges of which are slidably mounted in the grooves 25 of the strips 22. Mounted on adjacent edges of the doors 27, 27a are reinforcing strips 28, 28a which are adapted to strike the strips 26 in limiting opening movement of the doors, one of the doors, the door 27, being shown in open position in Fig. 2 of the drawing. The strip 28a includes at its outer surface a projecting beaded flange portion 28b which overlies the strip 28 to form a neat finish between the doors when in closed position.

At the outer edges of the doors 27, 27a are other reinforcing strips 29, 29a having beaded outer surfaces. These strips also strike the stop strips 26 in limiting closing movement of the doors as is indicated at the right of Fig. 2 of the drawing where the door 27a is shown in closed position. Upper and lower edges of the strips 28, 28a, 29, 29a, will have tongues projecting into the grooves 25 in further guiding the doors in their movement from open to closed positions.

It will appear from a consideration of Fig. 2 of the drawing that the sliding doors are maintained within the boundary limits of the side of the cabinet when in their open position so as to prevent engagement with walls or other surfaces that may be disposed adjacent the sides of the cabinet, particularly when used in restricted places. It will be apparent, however, that in some types of construction, the doors may be made wider and the door frame opening made larger to extend the sides of the door beyond the boundaries of the cabinet where this type of construction will not be objectionable. Such a construction has been shown in Fig. 6 of the drawing. Since the constructions of Figs. 2 and 6 are identical except for the relative size of the wall portions 20, 27a, the parts in these two figures have been identified by the same reference numerals.

With my construction, the door frame unit 14 will be factory assembled so that the purchaser has to contend only with four cabinet parts and whatever hanger accessories and the like may be employed, the same being omitted as they are commonly known to its users in this art. In collapsing the parts, the front wall part 13 is collapsible upon the bottom wall and the side flanges 14a of the part 14 are collapsible upon the panels 20. The front flange 11b may be folded upon the top wall part, the side walls 16 being foldable on one another and upon the back wall 15, as will be apparent.

In assembling the various cabinet parts the part 12 will be first arranged upon the floor, after which the part 10 will be placed upon the part 12 when in the position shown in Fig. 1. Fastener devices, as at 17a, will be inserted to couple the parts together, after which the door frame part 14 will be mounted in position with the flanges 14a disposed outwardly of the wall 16. Other fastening device, as at 17b, will be passed through the strips 18a, flanges 14a, and the wall 16 in securing the door frame in position. The upper edge of the front wall 13 is placed in the groove 23 of the lower strip 22. The top wall part 11 is then placed in position, the edge of the flange 11b being placed in the groove 23 of the top strip 22, and fasteners, as at 17c, will be passed through outwardly directed extensions of the reinforcing strips 18a and the parts 11c as will be apparent. The fasteners 17a, 17b and 17c are shown in Figs. 3 and 4 of the drawing.

From the foregoing it will be apparent that the cabinet may be quickly and easily assembled for use. By reason of the simplicity in the construction of the complete device, a cabinet of this type and kind may be made to sell at a reasonable price. The beaded portions on the rails 29, 29a as well as the bead 28b on the rail 28a will facilitate the operation of the doors in moving the same into open and closed positions. It will also be understood that by disposing the door frame unit at the upper portion of the cabinet, the operation of the doors will be simplified and the doors will be made sufficiently long to facilitate free insertion and removal of the clothing with respect to the cabinet.

Having fully described my invention, what I claim as new and desire to secure by Letters Patent, is:

1. A collapsible cabinet of the class described comprising four detachably coupled parts, one part comprising back and side walls of the cabinet, another part the top wall, another part the bottom wall, and the last of said parts comprising a door frame unit, said door frame unit comprising vertically arranged side panels joined by top and bottom door guiding rails, means coupling said door frame unit with the side walls of the first named part and with angularly extending flange portions of the top and bottom parts, said top and bottom rails and side panels forming in the door frame part a door opening, two vertically arranged panel-like door members arranged on and movable over said panels and slidably engaging the top and bottom rails in controlling said door opening, means comprising reinforcing parts on the door members and on said panels limiting the movement of said door members in both directions, the width of the door members in comparison with the width of the side panels and the door frame being such as to maintain the doors within boundary limits of

the sides of the cabinet when the doors are in fully opened position.

2. A collapsible cabinet of the class described comprising four detachably coupled parts, one part comprising back and side walls of the cabinet, another part the top wall, another part the bottom wall, and the last of said parts comprising a door frame unit, said door frame unit comprising a rectangular frame having top and bottom door guiding rails joined by stop rails bordering side edges of the door opening in said frame, said door frame unit and top and bottom walls having flanges extending onto predetermined walls of the first named part and attached thereto, the flanges of the top and bottom walls being in co-planar alignment with the flanges of said door frame part, and reinforcing strips supported on the flanges of said parts and cooperating to form reinforcing frames at the sides of the cabinet.

3. A collapsible cabinet of the class described comprising four detachably coupled parts, one part comprising back and side walls of the cabinet, another part the top wall, another part the bottom wall, and the last of said parts comprising a door frame unit, said door frame unit comprising a rectangular frame having top and bottom door guiding rails joined by stop rails bordering side edges of the door opening in said frame, said door frame unit and top and bottom walls having flanges extending onto predetermined walls of the first named part and attached thereto, the flanges of the top and bottom walls being in alignment with the flanges of said door frame part, reinforcing strips supported on the flanges of said parts and cooperating to form reinforcing frames at the sides of the cabinet, two panel-like door members arranged vertically in said door frame, each door member having a reinforcing strip at each side edge thereof, said door members slidably engaging the top and bottom rails of the door frame, and the reinforcing strips of said door members cooperating with said stop strips of the frame in limiting opening and closing movement of said door members.

4. A collapsible cabinet of the class described comprising four detachably coupled parts, one part comprising back and side walls of the cabinet, another part the top wall, another part the bottom wall, and the last of said parts comprising a door frame unit, said door frame unit comprising a rectangular frame having top and bottom door guiding rails joined by stop rails bordering side edges of the door opening in said frame, said door frame unit and top and bottom walls having flanges extending onto predetermined walls of the first named part and attached thereto, the flanges of the top and bottom walls being in alignment with the flanges of said door frame part, reinforcing strips supported on the flanges of said parts and cooperating to form reinforcing frames at the sides of the cabinet, two panel-like door members arranged vertically in said door frame, each door member having a reinforcing strip at each side edge thereof, said door members slidably engaging the top and bottom rails of the door frame, the reinforcing strips of said door members cooperating with said stop strips of the frame in limiting opening and closing movement of said door members, said top and bottom walls being both provided with angular extending front flange or wall portions, and said top and bottom rails having grooves receiving the said last mentioned flanges.

5. In a cabinet of the class described employing collapsibly related top, bottom and back and side wall parts forming a large door opening at the front of the cabinet, a door frame unit detachably connected with the first named parts and comprising a rectangular frame having top and bottom grooved door guiding rails joined by spaced vertical rails bordering the sides of the door opening formed in said door frame, means on the frame for coupling the same with the first named parts of the cabinet to close the opening in the cabinet, said means including side panels secured to said vertical rails and having foldable flanges adapted to overlie forward edges of said back and side wall part, a pair of vertically extending door members arranged on and movable over said panels and slidably engaging the top and bottom rails of the door frame in controlling the door opening of said frame, and means comprising reinforcing parts on the door members and said vertical rails of the frame for limiting opening and closing movement of said door members.

6. A door frame unit for the opening of cabinets of the class described, said unit comprising a rectangular frame consisting of spaced door guiding rails coupled together by panels joining the ends of the rails, said panels and rails having means for coupling the same with predetermined walls of the cabinet to retain the frame against displacement from the cabinet and in closing the cabinet opening, opposed edges of the panels having reinforcing and door stop strips coupling said door guiding rails and forming in conjunction with said rails the door opening of said frame, a pair of door members slidably engaging said rails and movable over the surfaces of said panels in moving the door members from a closed to an open position, and the edges of the door members having reinforcing and finishing strips cooperating with the stop strips to limit opening and closing movement of said door members.

7. A door frame unit for the opening of cabinets of the class described, said unit comprising a rectangular frame consisting of spaced door guiding rails coupled together by panels joining the ends of the rails, said panels and rails having means for coupling the same with predetermined walls of the cabinet to retain the frame against displacement from the cabinet and in closing the cabinet opening, opposed edges of the panels having reinforcing and door stop strips coupling said door guiding rails and forming in conjunction with said rails the door opening of said frame, a pair of door members slidably engaging said rails and movable over the surfaces of said panels in moving the door members from a closed to an open position, the edges of the door members having reinforcing and finishing strips cooperating with the stop strips to limit opening and closing movement of said door members, and said first named means comprising foldable flanges at outer edges of said panels and reinforcing strips extending longitudinally of said flanges.

8. A door frame unit for the opening of cabinets of the class described, said unit comprising a rectangular frame consisting of spaced door guiding rails coupled together by panels joining the ends of the rails, said panels and rails having means for coupling the same with predetermined walls of the cabinet to retain the frame against displacement from the cabinet and in closing the cabinet opening, opposed edges of the panels having reinforcing and door stop strips

coupling said door guiding rails and forming in conjunction with said rails the door opening of said frame, a pair of door members slidably engaging said rails and movable over the surfaces of said panels in moving the door members from a closed to an open position, the edges of the door members having reinforcing and finishing strips cooperating with the stop strips to limit opening and closing movement of said door members, said first named means comprising foldable flanges at outer edges of said panels and reinforcing strips extending longitudinally of said flanges, and said first named means also including grooves formed in outer edges of said rails.

9. A door frame unit for cabinets of the class described comprising two rails having a pair of grooves extending longitudinally of one edge, and a single groove longitudinally of the opposed edge, panels mounted in one of the first named grooves of each rail in coupling end portions of said rails, reinforcing strips at opposed edges of the panels and coupled with the rails adjacent the end portions thereof, said strips in conjunction with the rails forming a door opening in said frame, said panels having at their outer edges foldable flange portions, a pair of door members slidably engaging the other grooves of said rails and movable over the surfaces of the panels in moving the door members from a closed to an open position, and the first mentioned re-

inforcing strips cooperating with means on said door members for limiting opening and closing movement of said door members.

10. A collapsible cabinet of the class described comprising four detachably coupled parts, one part comprising back and side walls of the cabinet, another part the top wall, another part the bottom wall, and the last of said parts comprising a door frame unit, said door frame unit comprising a rectangular frame having top and bottom door guide rails joined by stop rails bordering side edges of the door opening in said frame, front side panels extending from said stop rails in the direction of the ends of said guide rails, said door frame unit and top and bottom walls having flanges extending onto predetermined walls of the first-named part and attached thereto, the flanges of the top and bottom walls being in co-planar alignment with the flanges of said door frame part, reinforcing strips supported on the flanges of said parts and cooperating to form reinforcing frames at the sides of the cabinet, the width of the door members in comparison with the width of the front side panels of said door frame being such as to provide for extension of the doors beyond the boundary limits of the sides of the cabinet when the doors are in fully open position.

HARRY DERMAN.
